(57) The ornamental design for an acupressure apparatus, as shown and described.

DESCRIPTION

FIG. 1 is a front elevation view of an acupressure apparatus, showing my new design, the rear elevation view being identical;

FIG. 2 is a left side elevation view thereof, the right side view being identical;

FIG. 3 is a top plan view thereof;

FIG. 4 is a bottom plan view thereof; and,

FIG. 5 is a bottom perspective view thereof.

The broken lines in the drawings depict portions of the acupressure apparatus that form no part of the claimed design.
